Primary Examiner — Freda S Nunn(74) *Attorney, Agent, or Firm* — Lerner, David, Littenberg, Krumholz & Mentlik, LLP(57) **CLAIM**

The ornamental design for a notebook computer housing, as shown and described.

DESCRIPTION

FIG. 1 is a front perspective view of a notebook computer housing according to my design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

Broken lines are environmental only and form no part of the claimed design.

Dash-dot lines adjacent un-shaded areas represent bounds of the claimed design and form no part of the claimed design themselves.

Stipple-fill areas represent portions of the design that have a color that contrasts with a color of the non-filled areas.
